(57) **CLAIM**

We claim the ornamental design for a dashboard for vehicle, as shown and described.

DESCRIPTION

FIG. 1 is a front perspective view of a dashboard for vehicle showing our new design according to a first embodiment; FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is another front perspective view thereof;

FIG. 9 is a front perspective view of a dashboard for vehicle showing our new design according to a second embodiment;

FIG. 10 is a front view thereof;

FIG. 11 is a rear view thereof;

FIG. 12 is a left-side view thereof;

FIG. 13 is a right-side view thereof;

FIG. 14 is a top view thereof;

FIG. 15 is a bottom view thereof;

FIG. 16 is another front perspective view thereof;

FIG. 17 is an enlarged view of the portion 17 encircled in FIG. 9;

FIG. 18 is an enlarged view of the portion 18 encircled in FIG. 10; and,

FIG. 19 is a front perspective view thereof showing an example state of use.

The evenly-dashed broken lines in the figures depict environmental subject matter and form no part of the claimed design.

The dot dash broken lines in the figures represent boundaries of the claimed design and form no part thereof.

The dot-dot-dash broken lines encircling portions of the claimed design that are illustrated in enlargements form no part of the claimed design.
